UNITED STATES PATENT OFFICE.

GEORGE W. WHITMAN, OF PLEASANTON, KANSAS, ASSIGNOR OF ONE-HALF TO EARNEST DECKER, OF PLEASANTON, KANSAS.

RAIL-JOINT.

No. 800,253.

Specification of Letters Patent.

Patented Sept. 26, 1905.

Application filed February 24, 1904. Serial No. 195,055.

To all whom it may concern:

Be it known that I, GEORGE W. WHITMAN, a citizen of the United States, residing at Pleasanton, in the county of Linn and State of Kansas, have invented certain new and useful Improvements in Rail-Joints, of which the following is a specification.

For a full description of the invention and the merits thereof and also to acquire a knowledge of the details of construction of the means for effecting the result reference is to be had to the following description and accompanying drawings, in which—

Figure 1 is a perspective view showing a rail-joint having the invention applied thereto. Fig. 2 is a side elevation. Fig. 3 is a transverse section. Fig. 4 is a detail perspective view of the angle-bar peculiarly formed to facilitate attachment of the rail-bond.

Corresponding and like parts are referred to in the following description and indicated in all the views of the drawings by the same reference characters.

This invention embodies a special form of rail connection, including peculiar bond for electrically connecting rails such as are used on city and suburban car-lines as one side of the electric circuit supplying motors of electrically-propelled cars traveling on such lines.

In the drawings the numeral 1 designates the rails, through which fastening-bolts 2 pass, said rails resting at the ends on a base-plate 3, having the pendent web 4. Angle-bars 5 and 6 are arranged at opposite sides of the rails at the ends, the fastenings 2 passing therethrough, the angle-bar 5 having the horizontal flange thereof provided with lugs 7, coacting with the key-bar 8 to lock the nuts 9 on the bolts 2 from displacement. Lock-pins 10 pass through the ends of the key-bar 8 to prevent displacement thereof. The bolts 2 have square heads 11, abutting with shoulders 12 on the outside of the vertical portion α of the angle-bar 6. The rail-bond embodies the usual bond-wires 14, the upper edge portions of the vertical parts α of said angle-bars 5 and

6 being cut away, as shown at 13, to admit of attachment of the ends of the bond-wires 14 to the ends of the rails 1. The portions 13 of each angle-bar are locked on opposite sides of 50 the point at which the ends of the rails meet and form cleared spaces between the upper edge portions of the angle-bars and the head portions of the rails, through which the ends of the bond-wires 14 pass. The attachment 55 of the bond-wires is such that the parts 5 and 6 may be readily cast to form the portions 13, through which the ends of the bond-wires pass. Further, the ends of the bond-wires are accessible to repair the connection of the same 60 with the rails without removal of the angle-bars, and the angle-bars may be removed without detaching the bond-wires. The attachment of the bond-wires is also such as to permit the rails to contract and expand without 65 liability of the ends of the bond-wires becoming detached.

Having thus described the invention, what is claimed as new is—

In a device of the class described, the combination of the rails 1, the angle-bars at opposite sides of the rails and having the vertical portions α of said angle-bars in contact with the under sides of the head portions of the adjacent rails 1, said vertical portions α being provided with the cut-away portions 13 extending downwardly from their upper edges, the cut-away portions 13 being located upon opposite sides of the point at which the ends of the rails meet and forming clearance-spaces 70 between the upper edge portions of the angle-bars and the head portions of the rails, and bond-wires 14 having their ends passing through the cut-away portions 13 of the angle-bars and attached to the sides of the rails, for 75 80 85 the purpose set forth.

In testimony whereof I affix my signature in presence of two witnesses.

GEORGE W. WHITMAN. [L. s.]
